UNITED STATES PATENT OFFICE.

CHARLES O. TAPPAN, OF NEW YORK, N. Y.

METHOD OF CONSTRUCTING THE IMPERVIOUS ELEMENT OF EARTH DAMS.

Application filed January 10, 1922. Serial No. 528,214.

To all whom it may concern:

Be it known that I, CHARLES O. TAPPAN, a citizen of the United States, a resident of New York, in the county of New York and 5 State of New York, have invented certain new and useful Improved Methods of Constructing the Impervious Element of Earth Dams, of which the following is a specification.

10 My invention relates to an improved method of constructing the impervious element of earth dams and has for its object to provide an improved method of constructing the impervious element or so-called core 15 section of earth dams used for the storage of water and comprises a method of collecting suitable impervious material, either with or without a blending of different materials, and of placing it in the dam in such 20 a manner as to form a homogeneous impervious mass.

Other objects of my invention will be apparent from the following description and from the accompanying drawings of illustrative embodiments thereof, in which—

25 Figure 1 is a plan of an illustrative dam; Figure 2 a vertical section taken on the line 2—2 of Figure 1 looking in the direction of the arrows and showing a valley 30 with a completed dam;

Figure 3 a vertical section taken on the line 3—3 of Figure 1 looking in the direction of the arrows and illustrating the pervious and impervious portions of the dam;

35 Figure 4 a plan of an illustrative dam, an impounding reservoir for collecting impervious material, and of sluicing areas from which the impervious material is collected;

40 Figure 5 a plan of an illustrative dam, impounding enclosures for collecting impervious material, and of sluicing areas from which the impervious material is collected; and

45 Figure 6 a vertical section taken on the line 6—6 of Figure 5 looking in the direction of the arrows and showing in section an impounding enclosure and sluicing area.

Similar reference characters refer to similar parts throughout the drawings.

A typical earth dam is illustrated in Figures 1, 2, and 3 of the drawings. The center section 1 of the earth fill composing the dam (Figure 3) is formed of impervious 55 material, and the outside sections 2 are formed of pervious or semi-pervious mate-

rial, the center section or core 1 constituting the watertight, cut-off element, designed to give water tightness to the structure.

The methods adopted for constructing 60 earth dams heretofore may be classified in general as the dry method, the hydraulic fill method, and the semi-hydraulic method.

1. By the dry method, the pervious or semi-pervious outside sections are composed 65 of dry earth or gravel delivered in place by scrapers, wagons, railroad cars, or other suitable appliances, and leveled and compacted by means of drags, harrows, or similar implements. The center impervious element or core is formed of dry clay and loam deposited in layers, sprinkled and rolled with grooved rollers to compact it into a solid mass designed to serve as the watertight, cut-off element of the structure. Frequently suitable impervious materials are 70 not available at the site and must be brought from a distance at great expense, and under conditions where impervious material is available it often is found in small scattered quantities or in such thin deposits as 75 to make the collection of it expensive and slow.

2. By the hydraulic fill method, where 80 there is adjacent the site material comprising a mixture of pervious and impervious material in such proportions as to furnish sufficient impervious material for the core by the use of water classification, earth 85 dams are built by delivering the material 90 into the fills hydraulically, either by means of sluicing with streams of water under pressure from deposits higher than the dam, or by elevating the material into place by means of hydraulic dredges. By this method 95 of construction the mixture of pervious and impervious material is delivered on to the outside pervious or semi-pervious sections of the dam. A pool of water is carried between the fills so formed, into which 100

settles by water classification in the center section forming the core, the fine elements and the impervious elements such as the clay and loam, so that if there is a sufficiency of these elements in the material an 105 impervious core is formed. Heretofore it has not been possible to build earth dams by the hydraulic fill method where the available material did not contain sufficient impervious elements to form the center impervious core.

3. By the semi-hydraulic method, material

is deposited in the outer pervious sections of the dam by railroad cars or other appliances, and the inner faces of the embankment so formed are sluiced with a powerful stream of water so that the impervious elements in the fill such as clay and loam are separated hydraulically and settle in a pool, so that by water classification an impervious core is created from the material sluiced from the 10 side fills in a manner somewhat similar to the hydraulic fill method. In practice it often has been found that there was not sufficient impervious elements in the main fills and it also has proved difficult to control 15 the boundaries of the impervious core.

My improved method of constructing the 20 impervious core for earth dams consists of collecting the impervious material by ground-sluicing it with a stream of water 25 from sluicing areas 5 into a reservoir site 6 such as is illustrated in Figure 4, preferably located on a small body of water as a pond, creek, brook, or stream 4. The collected material then is conveyed into the dam between the pervious fills and preferably allowed to consolidate in water as in the hydraulic fill method of construction, or conveyed first to a sump or open tank from which it may be pumped or otherwise 30 conveyed into place in the dam.

Where the deposits of suitable material are located in thin layers along the slopes of hills, as illustrated in Figures 5 and 6, the 35 impervious material may be collected by ground-sluicing areas 5 with a stream of water, and conveying the impervious material and water (by flumes if required), into impounding enclosures 7 formed by brush dams 8 or other similar structures. 40 The material so collected may be conveyed directly into place in the dam or first conveyed to sumps or open tanks 9 to which sufficient water is added so that the mixture 45 preferably may be delivered by pumps 10 into place between the pervious fills 2 and consolidated under water (if desired) in accordance with the usual practice in the hydraulic fill method of construction.

The two methods may be combined in 50 whole or in part according to the particular conditions encountered.

By means of my improved methods of construction, described above, the impervious material can be collected, delivered in place 55 in the structure of the dam, and better and more cheaply consolidated than by the dry method used heretofore. When used in combination with the hydraulic fill method of construction, it is possible by my improved 60 methods of construction to build dams hydraulically where from lack of suitable impervious elements in the material available for the hydraulic fills, the use of the hydraulic method would be impossible.

When used in combination with the semi-

hydraulic method of building dams, my improved methods of construction produce a more homogeneous impervious core and gives more accurate control of the location of the impervious element than is possible 70 with the semi-hydraulic method. It also is possible with my improved methods of construction to sample the material collected, and by blending or mixing the various materials, obtain an impervious material of the 75 best character obtainable from the available areas. Thus different reservoirs or impounding enclosures or suitably located sumps or open tanks may be constructed adjacent 80 areas of material varying as to imperviousness or suitability for core construction, and by blending as above described, a uniform and satisfactory impervious material is secured. Figure 5 of the drawings illustrates 85 two such different impounding areas 7, the materials collected in which may be blended or mixed in sump or open tank 9 in the proper proportion to use to best advantage the different materials obtained from the two separated sluicing areas 5.

Many modifications of my invention will be apparent to those skilled in the art without departing therefrom or from the scope of the claims, my invention not being limited to the embodiments chosen for purposes of 95 illustration but comprising a method of constructing the impervious elements of water retaining structures by impounding in reservoirs or enclosures impervious material collected by sluicing and then conveying the 100 same into place between the pervious sections of the structure adapted to retain the impervious portion, either directly or by way of intermediate sumps or open tanks, and comprising when necessary or advisable the 105 blending of material having varying characteristics of adaptability.

What I claim and desire to secure by Letters Patent is:

1. The method of constructing the impervious element or core section of earth dams which comprises collecting in impounding enclosures by ground sluicing with water, suitable material from areas accessible to the 110 dam site, blending the different material collected to produce the desired core structure, and conveying and placing the blended impervious material between the pervious outer sections of the dam so as to form a homogeneous impervious mass.

2. The method of claim 1 in which the material is blended in a suitably located sump or open tank to which water is added.

3. The method of claim 1 in which the material is blended in a suitably located sump or open tank to which water is added and the mixture pumped into place between the 125 pervious outer sections.

4. The method of constructing the impervious element or core section of earth dams 130

which comprises collecting suitable impervious material located in areas accessible to a reservoir site, by sluicing said material with a stream of water under pressure into said reservoir, and then conveying said collected impervious material into place between the pervious outer sections of the dam so as to form an impervious water-tight element or core section between them.

5 10 5. The process of claim 4 in which the collected impervious material is conveyed from the reservoir to a sump or open tank and from there conveyed into place in the dam.

6. The method of constructing the impervious element or core section of earth dams which comprises collecting suitable impervi-

ous material located on slopes by sluicing same from the areas containing it with a stream of water under pressure into an impounding enclosure formed on such slopes, 20 and then conveying the impervious material from said enclosure into place between the pervious outer sections of the dam.

7. The process of claim 6 in which the collected impervious material is conveyed from 25 the enclosure to a sump or open tank and from there conveyed into place in the dam.

In testimony that I claim the foregoing, I have hereunto set my hand this 28th day of December, 1921.

CHARLES O. TAPPAN.
